UNITED STATES PATENT OFFICE.

FRANKLIN J. HALES, OF BUSH'S STORE, KENTUCKY.

DOOR-SECURER.

SPECIFICATION forming part of Letters Patent No. 503,536, dated August 15, 1893.

Application filed February 14, 1893. Serial No. 462,273. (No model.)

To all whom it may concern:

Be it known that I, FRANKLIN J. HALES, a citizen of the United States, residing at Bush's Store, in the county of Laurel and State of Kentucky, have invented certain new and useful Improvements in Door-Securers; and I do hereby declare the following to be a full, clear, and exact description of the invention, such as will enable others skilled in the art to

10 which it appertains to make and use the same.

My invention relates to a portable door se- 15 curer which when not in use can be packed into a very small compass and put away in any suitable place, as will be hereinafter de- 20 scribed and claimed, whereby a door which is not provided with a fastening or is provided with an insecure fastening can be conveniently and quickly secured against opening from the outside.

25 In the accompanying drawings, Figure 1 is a perspective view of a door and portion of flooring with my invention applied to the same. Fig. 2 is a sectional view of a portion of a wall and ceiling with my door se- 30 curer applied to the same. Fig. 3 is a top view of the door se- 35 curer when folded up, the spring catch being shown in section, and Fig. 4 is a portion of the door se- 40 curer in an unfolded condition.

45 A in the drawings represents my door se- 50 curer which consists of two or more sections a, a', a^2 preferably three, each about one foot in length. The sections are joined together by a rule or buggy top joint B having a pin b passing through it which holds the sections 55 together whereby they are permitted to move in a half circle and when fully extended are prevented from moving around farther. The sections a, a^2 are each provided with a latch 60 C C. The latch consists of a housing c in which works a spring actuated bolt c' having a beveled nose c^2 , the bolt being normally held outward by the spring c^3 as shown. On op- 65 posite sides of the middle section a' in a plane 70 with the catches C C latch bars D D are piv- 75 otted and are provided at their outer ends with notches d, d which correspond to the shape of the beveled nose of the bolts c' so that when the sections are fully extended they will be 80 held in such condition by bringing the pivot- 85 ed latch bars D D in line with the latches C C by which action the latch bolts c' are forced

90 back into the recess until the bolt comes in line with the notches of the latch bars D D when they are pressed forward into said notch- 95 es by the springs and prevent the return or folding up of the sections until the bolts are drawn back. The pins d which pass through the hinge joints are extended outward a short distance, which, when the locking bars are 100 brought to a locking condition with respect to the bolts they are received by a recess formed in each of the latch bars D D for the purpose of stopping the further movement of the bar in that direction. The outer ends of 105 the sections a, a^2 are preferably beveled and are formed with penetrating points a^3, a^3 so that the door se- 110 curer can be applied to a door either from the floor or the ceiling as shown in Figs. 1 and 2.

115 In operation one end of the door se- 120 curer is applied at a suitable point in the floor or ceiling, in this instance the door, and the upper joint is slightly broken or arched as shown in dotted lines in Fig. 1 and the upper spiked 125 end of the se- 130 curer applied to the door where- 135 upon by pressing down on the arched joint the sections become straight or in the same plane, by reason of which a powerful thrust- 140 ing action is given to the door se- 145 curer and be- 150 ing fixed in the floor and door causes the pen- 155 etrating points to become further embedded in the door and floor and to hold the former closed by a powerful wedging action. To prevent 160 pressure on the outside of the door breaking 165 the joint, the latch bar is brought into use and is pressed against the beveled end of the latch bolt which presses the latter back until it 170 comes in coincidence with the notch in the end of the latch bar when it is forced by the 175 spring into the same and holds the joint 180 locked. It is obvious that when it is desired 185 to remove the door se- 190 curer it is simply neces- 195 sary to lift the locking bolt and break the joint.

200 The operation would be the same whether the door se- 205 curer is applied to the door and floor or to the ceiling and door; and it will be observed that by constructing the door se- 210 curer with three sections it can be folded into a small space as shown in Fig. 3 and in the event of a person traveling can be conveniently 215 packed in a valise.

220 What I claim as my invention is—

1. A door securer provided with penetrating points at its outer ends and comprising two or more jointed sections, a spring actuated locking bolt provided on one of the sections, a locking bar pivotally connected to another section which is adapted to have its free end brought in contact with the bolt and held by the same, substantially as described.
2. In a door securer, the combination of two or more sections united by suitable joints so that the sections can be compactly folded together, pins passed through the joints and extended laterally from the same, latches on the sections provided with spring actuated bolts,

latch bars provided with side notches and pivoted by one of their ends, their free ends being adapted to be brought in contact with the spring actuated bolts and be held from movement by said bolts and the pin which passes through and extends from the joints, substantially as described.

In testimony whereof I hereunto affix my signature in presence of two witnesses.

FRANKLIN J. HALES.
